DEVICE FOR FILLING A RECEPTACLE, COMPRISING AUTOMATIC STOPPING MEANS

Louis Auguste Carriol, Aulnay-sous-Bois, France, assignor to S. A. T. A. M. Societe Anonyme pour Tous Appareillages Mecaniques, La Courneuve, France

Application April 6, 1954, Serial No. 421,289

Claims priority, application France and Canada April 14, 1953

6 Claims. (Cl. 141—209)

This invention relates to receptacle filling devices having an automatic stop acting to cause cessation of the delivery of liquid into a receptacle when liquid therein reaches a chosen level, and has for its object to provide improvements in the automatic stop device described and claimed in my copending application Serial Number 319,985, filed November 12, 1952, and entitled "Combined Valve and Shut-off Means Therefor," now Patent No. 2,787,294, dated April 2, 1957.

According to one feature of the present invention, in a receptacle filling device according to a feature of the said application a second jet nozzle and pressure intake are provided, the pressure in the second pressure intake being controlled by second air admission means obturated by liquid in the receptacle at a level therein below that to which filling is required, the arrangement being such that the pressure in both pressure intakes is applied to the piston until the said second air admission means is obturated by the liquid, and the movement of the piston resulting from such obturation closes a conduit through which pressure in said second pressure intake is transmitted to the piston.

According to another feature of the invention in a receptacle filling device according to the said application the second auxiliary valve is opened by the initial movement of the manually operated means.

In a device as set forth in the last preceding paragraph, and having the duct connecting the face of the piston on which pressure acts to open the main valve and the upstream side of the said main valve formed in the main valve, a third auxiliary valve may be provided, the said third auxiliary valve being urged by resilient means to a position such that it opens the said duct when the main valve is closed, and being closed by a partial opening of the main valve sufficient to produce a flow in the jet nozzle capable of retaining the main valve open.

According to another feature of the invention, a fusible plug is provided which, when fused, permits escape of the pressure produced at the pressure intake and allows the main valve to close.

According to another feature of the invention, a cavity is provided in the shroud to accommodate a solid obturating member, the arrangement being such that the said obturating member lies in said cavity when the device is in a normal position for delivery of liquid, but moves from said cavity to disturb the jet when the device is in any other position.

The invention is hereinafter described with reference to the accompanying drawings, in which:

Figure 1 is a diagrammatic illustration of one arrangement according to the present invention.

Figure 2 is a sectional elevation of another arrangement according to the present invention; and

Figure 3 is a detail of Figure 2 drawn on an enlarged scale.

Referring to Figure 1, which shows an arrangement closely resembling that described with reference to Figure 12 of the drawings of the said application No. 319,985,

the main valve 2 is associated with a piston 9 as described in that application.

The by-pass 11 leads to two injectors 12a and 12b and to two pressure intakes 13a and 13b which are located at different levels in the tank to be filled. The intakes 13a and 13b are connected to the cylinder 9b at different heights by the conduits 15a and 15b.

Finally, a cock 5 controls a by-pass 1c of the conduit 1 supplying the liquid, as described in the parent application.

The operation of this device is as follows:

In order to fill the tank, the cock 5 is opened and the pressure liquid, by acting on the face 9d, lifts the piston 9 and the valve 2. The opening of the said valve 2 enables the liquid to penetrate into the tank and into the conduit 11. The jets 12a and 12b send forth streams of substantially cylindrical shape, the cross-section of which is substantially equal to the cross-section of the orifices of the jets 12a and 12b and which streams strike the pressure intakes 13a and 13b as in the preceding examples.

The pressures produced in the intakes 13a and 13b are transmitted via the conduit 15a and 15b to the chamber 9e. The cock 5 is now closed. The intakes 13a and 13b maintain within the chamber 9e a pressure which suffices to keep the valve 2 open despite the thrust exerted on the piston by the liquid coming from the conduit 1. When the liquid level reaches the ejector 12b, the pressure of the intake 13b falls and the liquid within the chamber 9e is urged through the conduit 15b which acts as an escape and causes the pressure to fall in the chamber 9e. The valve 2 closes until the piston 9 blocks the conduit 15b and the flow therefore continues at reduced speed until the ejector 12a is in its turn immersed in the liquid. At this moment the pressure of the intake 13a falls, the liquid in the chamber 9e is evacuated through the conduit 15a, and the valve 2 is completely closed.

It should be pointed out that the by-pass 1c and the cock 5 might be eliminated, a spring being then provided in the chamber 9e, to urge the valve towards its open position. The mere force of the said spring is alone insufficient to prevent the closure of the valve 2 when the flow of liquid through the conduit 1 is normal. On the other hand, the force of this spring alone is sufficient to open the valve 2 when the pressure of the fluid in that part of the main conduit 1 which is situated up-stream of the main valve 2 falls. In this case, at the moment when this part of the main conduit 1 is subjected to pressure, the valve 2 is opened and the pressure intakes 13a and 13b come into action immediately creating pressure in the chamber 9e which, with the aid of the said spring, suffices to keep the valve 2 open. When the action of the said intakes 13a and 13b ceases, the force of the said spring, which is now the only force, is insufficient to oppose the closing of the valve 2 under the effect of the liquid pressure for a normal flow. The valve 2 thus closes automatically and only reopens when the pressure has dropped sufficiently. This arrangement also enables the receptacle to be emptied through the filling orifice.

In most of the examples described in the parent application, the jet 12 and the tube 13 are arranged in an enclosed chamber 11c. The existence of the said chamber, although recommended, is not necessary, particularly in the case in which the jet 12 and the tube 13 are liable to be flooded by the liquid located within the receptacle which is to be filled, as shown in Figure 6 of the parent application.

The device shown in Figure 2 differs from that shown in Figure 5 of said application Serial No. 319,985 more particularly by the following points:

(a) The end of the chamber 11c which accommodates the member 13 is open instead of closed;

(b) The press-button 5 of Figure 5 is replaced by a

member 5a controlled by a lever 5 similar to the lever of the nozzles shown in Figures 1 to 4 of the parent application;

(c) The shaft 7 is rigidly secured to the valve 20;

(d) The conduit 9f, which is closed as in Figure 5 by the two auxiliary valves 20 and 20a, is also closed in certain positions up-stream of the said valves 20 and 20a by a third auxiliary valve 20b which is subjected to the action of a spring;

(e) A ball 24a is located in a cavity 24 which opens into the chamber 11c and is so inclined that in the positions corresponding to normal use of the nozzle the ball 24 remains in the cavity 24a and emerges therefrom in all other positions;

(f) A plug 25a consisting of a readily fusible material seals a conduit 25 which connects the chamber 9e to the exterior.

The operation of this latter type of nozzle is as follows:

In order to fill a tank, the end of the hose-cock is inserted into the said tank until the orifice 17 is located at the stop level which is to cause the cessation of the filling. After the operator has set the supply pump in operation, he presses on the lever 5 against the spring 16. This has as its immediate effect the removal of the valve 20 from its seating. The valve 20a then opens, despite the action of the spring 10, because of the pressure prevailing in that part of the conduit 1 which is situated up-stream of the valve 2, the valve 20b remaining off its seat. Under these conditions, the up-stream pressure is transmitted to the face 9d of the piston. Under the influence of the various pressures acting on the assembly consisting of the valve 2 and the piston 9, the valve 2 opens until the valve 20 is overtaken by the shoulder of the conduit 9f, said shoulder forming the seat of the valve 20. The conduit 9f is then again closed. Two cases may occur:

First case.—The flow through the by-pass 11 is insufficient to ensure in the intake 13 a pressure which is of itself sufficient to keep the valve 2 open. In this case, as soon as the conduit 9f is closed, the valve 2 tends to be closed until it reaches a position slightly less open than the position corresponding to closing of the conduit 9f by the valve 20. Thus it is possible to regulate as desired the quantity of the flow by displacing the lever 5 more or less, but it must be pointed out that the closing of the hose-cock is no longer automatic and depends on the will of the operator.

Second case.—The flow in the by-pass 11 is sufficient to ensure a pressure in the intake 13 sufficient to maintain the valve 2 open. In this case, the liquid flows away through the slot 11a in the by-pass 11 and emerges from the jet 12 in the form of a stream which strikes the pressure intake 13 as in the case of Figure 5 of said application Serial No. 319,985. As described with reference to that figure, the valve 2 also tends to a large opening but is prevented therefrom in this case by the valve 20 which forms a stop. The instant at which the valve 20 serves as a stop depends on the state of compression of the spring 16, which depends on the wish of the operator. Thus the latter can, by means of the lever 5, regulate the extent to which the spring 16 is compressed and so regulate the degree of opening of the valve 2. When the opening of the latter is sufficiently large, the valve 20b closes the inlet up-stream of the conduit 9f, this latter action not causing any inconvenience since the pressure of the intake 13 on the face 9d is sufficient to maintain the valve 2 in its open position. When the liquid in the tank reaches the orifice 17, the air no longer arrives by the conduit 19 and the orifice 18. The stream of liquid issuing from the nozzle 12 fans out immediately after egress from the said nozzle and loses speed. The pressure drops and possibly disappears altogether in the intake 13. The pressure on the face 9d therefore falls. The resultant pressure acting on the valve 2 and piston 9 is then such that the valve 2 closes. Closure of the valve

2 then shuts the by-pass 11 but during this displacement, the valve 20b, the cross-section of which is larger than that of the inlet of the conduit 9f, stays forced on its seat by the liquid pressure on its up-stream side, despite the return action of the spring 4b, which neutralises the effect of the opening of the said conduit 9f by the valve 20 in consequence of the descending movement of the piston 9, the lever 5 still being supposed to be held in one of its opening positions. After the closure of the valve 2 due to the pressure drop in the intake 13, if the operator completely releases the lever 5, the pressures on the two faces of the valve 20b are equalised as a result of the presence of a slot forming by-pass in the disc of said valve and the valve 20b is dislodged by the action of the spring 4b. The apparatus can then function again.

If the operator does not release the lever, the valve 20 remains open and impedes the balance between the pressures on the two faces of the valve 20b. The latter thus remains seated and prevents further flow.

If, by mistake, the operator drops the hose-cock while it is pouring, the said hose-cock cannot be kept balanced in a normal pouring position, since the ball 24a emerges from its cavity 24 by its own weight and locates itself in the trajectory of the stream issuing from the member 12, whence there results a disturbance in the chamber 11c and premature closing of the valve 2.

If a fire breaks out in the vicinity of the hose-cock the temperature rises and ends by melting the plug 25a, so that the pressure in the chamber 9 is relieved through the conduit 25 and the flow stops.

I claim:

1. A combined valve and shut-off means therefor, comprising, in combination, a valve casing having a fluid inlet and a fluid outlet and a valve seat therebetween; a main valve member in said valve casing movable between open and closed positions; fluid pressure operable means for holding said main valve member in open position, said main valve member automatically returning into closed position when exertion of fluid pressure on said fluid pressure operable means is terminated; a first fluid conduit having one end in communication with said valve casing at a first portion thereof intermediate said fluid inlet thereof and said valve seat thereof and the other end in communication with said fluid pressure operable means for actuating the same so as to hold said main valve member in open position when said first fluid conduit is filled with fluid under pressure; a first auxiliary valve member in said first fluid conduit movable between open and closed positions; moving means for moving said first auxiliary valve member between said positions thereof, said moving means including first biasing means for biasing said first auxiliary valve member to closed position and manually-operable means for moving said first auxiliary valve member to open position against the action of said first biasing means; a second auxiliary valve member also in said first fluid conduit movable between open and closed positions; second biasing means for biasing said second auxiliary valve member to closed position and for permitting said second auxiliary valve member to move to open position when said first auxiliary valve member is in open position; a second fluid conduit having an open end and the other end also in communication with said fluid pressure operable means for actuating the same so as to hold said main valve member in open position when said second fluid conduit is filled with fluid under pressure; a nozzle member in communication with said valve casing at a second portion thereof intermediate said valve seat thereof and said fluid outlet thereof and facing said open end of said second fluid conduit; and a third fluid conduit terminating at one end in the region intermediate said nozzle member and said open end of said second fluid conduit for admitting gaseous medium sucked into said region by the jet of fluid emitted by said nozzle member.

2. A combined valve and shut-off means therefor, com-

prising, in combination, a valve casing having a fluid inlet and a fluid outlet and a valve seat therebetween; a main valve member in said valve casing movable between open and closed positions; fluid pressure operable means for holding said main valve member in open position, said main valve member automatically returning into closed position when exertion of fluid pressure on said fluid pressure operable means is terminated; a first fluid conduit having one end in communication with said valve casing at a portion thereof intermediate said fluid inlet thereof and said valve seat thereof and the other end in communication with said fluid pressure operable means for actuating the same so as to hold said main valve member in open position when said first fluid conduit is filled with fluid under pressure; a first auxiliary valve member in said first fluid conduit movable between open and closed positions; moving means for moving said first auxiliary valve member between said positions thereof, said moving means including first biasing means for biasing said first auxiliary valve member to closed position and manually-operable means for moving said first auxiliary valve member to open position against the action of said first biasing means; a second auxiliary valve member also in said first fluid conduit movable between open and closed positions, said second auxiliary valve member being intermediate said first auxiliary valve member and said one end of said first fluid conduit; second biasing means for biasing said second auxiliary valve member to closed position and for permitting said second auxiliary valve member to move to open position when said first auxiliary valve member is in open position; a second fluid conduit having an open end located in said fluid outlet of said valve casing facing the fluid passing through said fluid outlet and the other end also in communication with said fluid pressure operable means for actuating the same so as to hold said main valve member in open position when said second fluid conduit is filled with fluid under pressure; a nozzle member also in said fluid outlet of said valve casing and facing said open end of said second fluid conduit; and a third fluid conduit terminating at one end in said fluid outlet of said valve casing and in the region intermediate said nozzle member and said open end of said second fluid conduit for admitting gaseous medium sucked into said region by the jet of fluid emitted by said nozzle member.

3. A combined valve and shut-off means therefor, comprising, in combination, a valve casing having a fluid inlet and a fluid outlet and a valve seat therebetween; a main valve member in said valve casing movable between open and closed positions; fluid pressure operable means for holding said main valve member in open position, said main valve member automatically returning into closed position when exertion of fluid pressure on said fluid pressure operable means is terminated; a first fluid conduit having one end in communication with said valve casing at a first portion thereof intermediate said fluid inlet thereof and said valve seat thereof and the other end in communication with said fluid pressure operable means for actuating the same so as to hold said main valve member in open position when said first fluid conduit is filled with fluid under pressure; a first auxiliary valve member in said first fluid conduit movable between open and closed positions; moving means for moving said first auxiliary valve member between said positions thereof, said moving means including first biasing means for biasing said first auxiliary valve member to closed position and manually-operable means for moving said first auxiliary valve member to open position against the action of said first biasing means; a second auxiliary valve member also in said first fluid conduit movable between open and closed positions; second biasing means for biasing said second auxiliary valve member to closed position and for permitting said second auxiliary valve member to move to open position when said first auxiliary valve member is in open position; a second fluid conduit

having an open end and the other end also in communication with said fluid pressure operable means for actuating the same so as to hold said main valve member in open position when said second fluid conduit is filled with fluid under pressure; a nozzle member in communication with said valve casing at a second portion thereof intermediate said valve seat thereof and said fluid outlet thereof and facing said open end of said second fluid conduit; a third fluid conduit terminating at one end in the region intermediate said nozzle member and said open end of said second fluid conduit for admitting gaseous medium sucked into said region by the jet of fluid emitted by said nozzle member; a fourth fluid conduit having one end in communication with said pressure operable means and the other end in communication with the exterior of said valve casing; and temperature-responsive closure means in said fourth fluid conduit for closing the same when the combined valve and shut-off means is subjected to normal ambient temperatures and for venting said fluid pressure operable means to atmosphere when the combined valve and shut-off means is subjected to abnormally high ambient temperatures so as to permit movement of said main valve member into closed position.

4. A combined valve and shut-off means therefor, comprising, in combination, a valve casing having a fluid inlet and a fluid outlet and a valve seat therebetween; a main valve member in said valve casing movable between open and closed positions; fluid pressure operable means for holding said main valve member in open position, said main valve member automatically returning into closed position when exertion of fluid pressure on said fluid pressure operable means is terminated; a first fluid conduit having one end in communication with said valve casing at a portion thereof intermediate said fluid inlet thereof and said valve seat thereof and the other end in communication with said fluid pressure operable means for actuating the same so as to hold said main valve member in open position when said first fluid conduit is filled with fluid under pressure; a first auxiliary valve member in said first fluid conduit movable between open and closed positions; moving means for moving said first auxiliary valve member between said positions thereof, said moving means including first biasing means for biasing said first auxiliary valve member to closed position and manually-operable means for moving said first auxiliary valve member to open position against the action of said first biasing means; a second auxiliary valve member also in said first fluid conduit movable between open and closed positions, said second auxiliary valve member being intermediate said first auxiliary valve member and said one end of said first fluid conduit; second biasing means for biasing said second auxiliary valve member to closed position and for permitting said second auxiliary valve member to move to open position when said first auxiliary valve member is in open position; a second fluid conduit having an open end located in said fluid outlet of said valve casing facing the fluid passing through said fluid outlet and the other end also in communication with said fluid pressure operable means for actuating the same so as to hold said main valve member in open position when said second fluid conduit is filled with fluid under pressure; a nozzle member also in said fluid outlet of said valve casing and facing said open end of said second fluid conduit; a third fluid conduit terminating at one end in said fluid outlet of said valve casing and in the region intermediate said nozzle member and said open end of said second fluid conduit for admitting gaseous medium sucked into said region by the jet of fluid emitted by said nozzle member; a fourth fluid conduit having one end in communication with said pressure operable means and the other end in communication with the exterior of said valve casing; and fusible sealing means in said fourth fluid conduit for sealing the same when the combined valve and shut-off means is subjected to normal

ambient temperatures and for venting said fluid pressure operable means to atmosphere when the combined valve and shut-off means is subjected to abnormally high ambient temperatures so as to permit movement of said main valve member into closed position.

5. A combined valve and shut-off means therefor, comprising, in combination, a valve casing having a fluid inlet and a fluid outlet and a valve seat therebetween; a main valve member in said valve casing movable between open and closed positions; fluid pressure operable means for holding said main valve member in open position, said main valve member automatically returning into closed position when exertion of fluid pressure on said fluid pressure operable means is terminated; a first fluid conduit having one end in communication with said valve casing at a first portion thereof intermediate said fluid inlet thereof and said valve seat thereof and the other end in communication with said fluid pressure operable means for actuating the same so as to hold said main valve member in open position when said first fluid conduit is filled with fluid under pressure; a first auxiliary valve member in said first fluid conduit movable between open and closed positions; moving means for moving said first auxiliary valve member between said positions thereof, said moving means including first biasing means for biasing said first auxiliary valve member to closed position and manually-operable means for moving said first auxiliary valve member to open position against the action of said first biasing means; a second auxiliary valve member also in said first fluid conduit movable between open and closed positions; second biasing means for biasing said second auxiliary valve member to closed position and for permitting said second auxiliary valve member to move to open position when said first auxiliary valve member is in open position; a second fluid conduit having an open end and the other end also in communication with said fluid pressure operable means for actuating the same so as to hold said main valve member in open position when said second fluid conduit is filled with fluid under pressure; a nozzle member in communication with said valve casing at a second portion thereof intermediate said valve seat thereof and said fluid outlet thereof and facing said open end of said second fluid conduit; a third fluid conduit terminating at one end in the region intermediate said nozzle member and said open end of said second fluid conduit for admitting gaseous medium sucked into said region by the jet of fluid emitted by said nozzle member; and interrupter means mounted for movement between an inoperative position wherein said interrupter means is exterior of the path of the jet of fluid projected by said nozzle member against said open end of said second fluid conduit and an operative position wherein said interrupter means is in said path, said interrupter means being in said inoperative position thereof when the combined valve and shut-off means is in its normal position and in said operative position thereof when the combined valve and shut-off means is in an abnormal position.

6. A combined valve and shut-off means therefor, comprising, in combination, a valve casing having a fluid inlet and a fluid outlet and a valve seat therebetween;

a main valve member in said valve casing movable between open and closed positions; fluid pressure operable means for holding said main valve member in open position, said main valve member automatically returning into closed position when exertion of fluid pressure on said fluid pressure operable means is terminated; a first fluid conduit having one end in communication with said valve casing at a portion thereof intermediate said fluid inlet thereof and said valve seat thereof and the other end in communication with said fluid pressure operable means for actuating the same so as to hold said main valve member in open position when said first fluid conduit is filled with fluid under pressure; a first auxiliary valve member in said first fluid conduit movable between open and closed positions; moving means for moving said first auxiliary valve member between said positions thereof, said moving means including first biasing means for biasing said first auxiliary valve member to closed position and manually-operable means for moving said first auxiliary valve member to open position against the action of said first biasing means; a second auxiliary valve member also in said first fluid conduit movable between open and closed positions, said second auxiliary valve member being intermediate said first auxiliary valve member and said one end of said first fluid conduit; second biasing means for biasing said second auxiliary valve member to closed position and for permitting said second auxiliary valve member to move to open position when said first auxiliary valve member is in open position; a second fluid conduit having an open end located in said fluid outlet of said valve casing facing the fluid passing through said fluid outlet and the other end also in communication with said fluid pressure operable means for actuating the same so as to hold said main valve member in open position when said second fluid conduit is filled with fluid under pressure; a nozzle member also in said fluid outlet of said valve casing and facing said open end of said second fluid conduit; a third fluid conduit terminating at one end in said fluid outlet of said valve casing and in the region intermediate said nozzle member and said open end of said second fluid conduit for admitting gaseous medium sucked into said region by the jet of fluid emitted by said nozzle member; and interrupter means in said fluid outlet of said valve casing and mounted for movement between an inoperative position wherein said interrupter means is exterior of the path of the jet of fluid projected by said nozzle member against said open end of said second fluid conduit and an operative position wherein said interrupter means is in said path, said interrupter means being in said inoperative position thereof when the combined valve and shut-off means is in its normal position and in said operative position thereof when the combined valve and shut-off means is in an abnormal position.
